US00D556250S

(12) **United States Design Patent** (10) **Patent No.:** **US D556,250 S**
Kent et al. (45) **Date of Patent:** **** Nov. 27, 2007**

(54) **SHREDDER**

(75) Inventors: **Michael Kent**, Cumberland, RI (US);
Gregg Draudt, Stow, MA (US);
Kristin Sjo-Gaber, Brookline, MA
(US); **Daniel A. Barry**, Berlin, MA
(US)

(73) Assignee: **Staples The Office Superstore, LLC**,
Framingham, MA (US)

(**) Term: **14 Years**

(21) Appl. No.: **29/268,091**

(22) Filed: **Oct. 30, 2006**

(51) **LOC (8) Cl.** **18-04**

(52) **U.S. Cl.** **D18/34.6**

(58) **Field of Classification Search** D18/34.1-34.9,
D18/99, 50; 83/167, 289, 302, 203, 523,
83/633; 241/169.1, 36, 154, 157, 222, 224,
241/168, 284, 295, 37.5, 100, 236; 385/13;
D8/99

See application file for complete search history.

(57) **CLAIM**

The ornamental design for a shredder, as shown and described.

DESCRIPTION

FIG. 1 is a side, top perspective view of a shredder showing our new design;

FIG. 2 is a front view thereof;

FIG. 3 is a left side view thereof;

FIG. 4 is a rear side view thereof;

FIG. 5 is a top view thereof; and,

FIG. 6 is a bottom view thereof.

The light broken lines shown in the drawings are for illustrative purposes only and represent the boundaries of the claimed design and form no part of the claimed design. The heavy broken lines are also for illustrative purposes only and represent environmental structures and form no part of the claimed design.

1 Claim, 2 Drawing Sheets
